UNITED STATES PATENT OFFICE.

GUSTAVE E. VILLARET, OF LEONIA, NEW JERSEY, ASSIGNOR TO WILLIAM R. NOE & SONS, OF NEW YORK, N. Y., A COPARTNERSHIP.

DESIGN FOR A LAMP.

Application filed May 21, 1924. Serial No. 9,684. Term of patent 7 years.

To all whom it may concern:

Be it known that I, GUSTAVE E. VILLARET, a citizen of the United States, residing at Leonia, in the county of Bergen and State of New Jersey, have invented a new, original, and ornamental Design for a Lamp, of which the following is a specification, reference being had to the accompanying drawing, forming part thereof.

Fig. 1 is a front elevation view of a lamp, showing my new design.

Fig. 2 is a side elevation of the same.

Fig. 3 is a diagrammatic outline of the base taken on the line 1—1 of Fig. 1 and looking in the direction of the arrows, only half of the figure being shown, it being understood that the other half is identical and is given to show the contour of the base.

I claim—

The ornamental design for a lamp, as

GUSTAVE E. VILLARET.
